United States Patent Office

Des. 227,891
Patented July 24, 1973

227,891

DENTAL CABINET MODULE

Robert G. Welsh, 4239 Redick, Omaha, Nebr. 68111

Filed June 19, 1972, Ser. No. 264,267

Term of patent 14 years

Int. Cl. D6—01; D24—03

U.S. Cl. D24—1 B

FIG. 1

FIG. 2

FIG. 3

FIG. 1 is a perspective view of a dental cabinet module showing my new design;

FIG. 2 is a right side elevational view thereof; and
FIG. 3 is a front elevational view thereof.

I claim:

The ornamental design for a dental cabinet module, substantially as shown.
